REFINING LUBRICATING OIL STOCK

William E. Forney, Merchantville, N. J., assignor
to Cities Service Oil Company, New York, N. Y.,
a corporation of Pennsylvania

Application July 9, 1936, Serial No. 89,714

8 Claims. (Cl. 196—13)

This invention relates to the refining of lubricating oil stocks and more particularly to a process of refining lubricating oil stocks in which a selective solvent is employed for removing undesirable constituents.

In recent years lubricating oil stocks have been refined by selectively removing certain undesirable constituents by the use of selective solvents instead of subjecting the oil to drastic treatment with concentrated sulfuric acid as commonly practiced in the past. Nitrobenzene, phenol and many other solvents have been proposed as a means for selectively removing certain constituents from lubricating oil stocks. The present invention is an improvement in this type of process.

The primary object of the invention is to provide a process for refining lubricating oil stocks by the use of a selective solvent adapted to selectively remove naphthenic and aromatic hydrocarbons as well as phenolic compounds from lubricating oil stocks.

Accordingly, the improved process comprises the steps of intimately contacting the oil to be refined with an alkyl sulfate (acid or normal) either alone or in admixture with sulfuric acid, continuing the contacting operation until the selective solvent has absorbed the undesirable naphthenic and aromatic constituents, separating the solvent containing the undesirable constituents from the purified oil and contacting the separated oil with a neutralizing agent.

Other features of the improved process of the present invention will be apparent to those skilled in the art from the following more detailed description thereof taken in connection with the accompanying drawing in which:

The single figure is a diagrammatic vertical view showing an apparatus particularly adapted for carrying out the improved process.

The alkyl sulfates used as a solvent in accordance with the present invention may be derived from any suitable source, but they may be made directly in connection with the process by suitably treating olefin gases with concentrated sulfuric acid. The olefin gases used comprise individual olefins or mixtures of olefins such as those obtained in the cracking of petroleum oils. A suitable mixture comprises cracking still gases containing ethylene, propylene, the butylenes and the amylenes.

The olefin gases used to make the alkyl sulfates may be introduced into the apparatus shown in the drawing through a line 2, and passed into the lower portion of a contact tower

4 in intimate contact with concentrated sulfuric acid which may be introduced through a line 6 and a cooler 8. The olefin gas mixture passes upwardly through a tower and is brought in intimate contact with the sulfuric acid which flows downwardly over a series of bubble trays countercurrently to the gases. The acid is therefore gradually converted into alkyl sulfates so that by the time it reaches the bottom of the tower 4 the acid mixture comprises sulfuric acid, acid alkyl sulfates and a very substantial proportion of di-alkyl sulfates.

When treating a mixture of olefin gases in the tower 4, the temperature is preferably controlled such that the olefins higher boiling than ethylene are principally reacted with the acid. The temperature at the top of the tower 4 therefore should not be substantially above 50° F. while the temperature at the bottom of the tower is preferably held as low as about 25° F. Where ethylene is treated alone for the manufacture of ethyl sulfate, the temperature at the top of the tower 4 should be about 125° F., and the temperature at the bottom of the tower about 50° F. The tower 15 4 is provided with temperature control coils 10 mounted in the liquid on each tray, and each coil is provided with an individual supply line 12 which connects into a main line 14 for supplying a temperature control medium such as brine or other fluid at the proper temperature. The coils 10 discharge through separate lines 16 into a line 18 from which the heat exchange medium may be sent to any desired point for temperature adjustment and then returned through the line 14 to the coils 10.

The contact of the olefin gases with concentrated sulfuric acid in the tower 4 necessarily produces a certain amount of polymerization of the gaseous olefins to normally liquid products. 20 This liquid material passes upwardly through the tower 4 along with the unabsorbed gas and is discharged with the unabsorbed gas through a valved line 20 into a separator 22 in which the gas and liquid are separated. The gas is withdrawn from the separator 22 through a valved line 24, while the liquid is withdrawn through a valved line 26. The mixture of alkyl sulfates and sulfuric acid is withdrawn from the tower 4 through a line 28 into a separator 30 in which any hydrocarbon material present may be separated and withdrawn through the valved line 32.

The alkyl sulfate or mixture of alkyl sulfates and sulfuric acid to be used in the oil refining process is withdrawn from the separator 30

through a line 34 and forced by means of a pump 36 through a line 38, a cooler 40 and one or more valved distribution lines 42, into the upper portion of a treating or extraction tower 44. Any sulfuric acid present may be removed from the alkyl sulfates in separator 30. The extraction tower 44 comprises a series of bubbler trays similar to that used in tower 4 and it also includes a cooling coil 46 mounted between each of the adjacent trays. Each of these coils 46 is supplied with a cooling fluid such as cold brine through individual valve supply lines 48 which connect with a main supply line 50. The coils 46 discharge through separate lines 52 into a main line 54.

The petroleum lubricating oil stock to be refined and which may be a distillate or residuum stock of a mixed base type is introduced into the extraction tower 44 (or other suitable contacting devices or chambers) through a valved supply line 56. Oil stock thus introduced is preferably diluted with a solvent such as liquid propane, butane or pentane which will materially reduce the viscosity and gravity of the oil. The oil may therefore comprise from 30% to 75% of such a hydrocarbon diluent. This oil mixture introduced through the line 56 passes upwardly through the tower 44 and on each tray intimately contacts the alkyl sulfate extraction agent introduced through one or more of the lines 42 into the upper part of the tower. As the alkyl sulfate extraction agent passes downwardly through the tower it selectively removes from the diluted oil such constituents as the naphthenic compounds, aromatic compounds and other compounds other than paraffin hydrocarbons. This extracted material together with the selective alkyl sulfate solvent is discharged from the bottom of the tower 44 through a valved line 58 and sent to a separator 60 since the extracting agent may contain small proportions of the oil introduced through the line 56. The separated oil is removed through a line 62 and reintroduced into the tower 44, while the extract is withdrawn through a line 64.

The oil introduced into the tower 44 through the line 56 passes upwardly through the tower and out through a valved line 66 into a separator 68. The separator 68 is used to remove any traces of the extracting agent which may be merely occluded in the oil. This extract is withdrawn from the separator through a line 70 and introduced into the tower 44, while the separated oil is withdrawn through a line 72. It is to be understood that separators 22, 30, 60 and 68 may be any type of normal gravity separator or centrifugal separator. In effecting the operation in tower 44, it is to be understood that suitable pressures may be maintained thereon to keep the liquid propane or other low boiling solvent in the liquid phase. Furthermore the temperatures in the tower may be accurately controlled by means of the cooling coils 46. The temperatures actually used in carrying out the process will depend to a considerable extent upon the composition of the extracting medium employed. With normal sulfates only, the temperature may be as high as 140° to 150° F.; whereas if sulfuric acid is present the temperature should not exceed about 40° F. or a temperature sufficiently low to avoid polymerization. Where a mixture of normal and acid sulfates with sulfuric acid is used, a temperature of 32° F. or lower should be employed.

The diluted and extracted oil discharged

through the line 72 (after removal of dissolved alkyl sulfate), is preferably brought in contact with some neutralizing agent such as fuller's earth or other clay, and then dewaxed. In this connection, it will be noted that the oil is already diluted with liquid propane for example, and that the dewaxing operation may be effectively carried out by vaporizing a portion of the propane to effect the refrigeration necessary for precipitating the wax in the oil mixture. The oil may then be filtered or otherwise treated for the separation of the precipitated wax in accordance with well-known practice. The clay or other alkaline treatment is particularly necessary where the extracting agent used in the tower 44 contains sulfuric acid.

Instead of carrying out the refining operation in the manner described above, the diluted lubricating oil stock may be treated simultaneously with the formation of alkyl sulfates in the tower 4. This may be accomplished by carrying out the operation described above in connection with tower 4 by introducing the diluted lubricating oil stock in at the base of the tower through a line 74 so that it enters the tower along with the olefin gas to be reacted with the sulfuric acid. Under these circumstances the lubricating oil stock passes upwardly through the tower counter-currently to sulfuric acid and alkyl sulfates which pass downwardly through the tower. A suitable difference in gravity between the diluted oil and the extracting medium is maintained to insure effective separation as the extraction proceeds. In this operation however, the lubricating oil stock discharged through the line 20 will have been contacted with concentrated sulfuric acid in the top of the tower, but this will have no detrimental effect upon the oil because of its dilution and because it contains substantially only paraffinic type hydrocarbons by the time it reaches the upper part of the tower 4 where it contacts the strong sulfuric acid. The oil discharged into the separator 22 will be removed through the line 26, freed of occluded acid, and then subjected to a clay treatment and dewaxing in the manner described above. Some oil may be separated out in the separator 30 and discharged through the line 32. This should be added to the oil introduced through the line 74. Where individual commercial extracting agents are to be used in the process, such for example as diethyl sulfate, diisopropyl sulfate, the butyl sulfates, the amyl sulfates, or the acid alkyl sulfates, the operation may be effectively carried out in the tower 44 by introducing the extracting agent into the top of the tower through a valved line 76. The operation then will be carried out in the manner described above in connection with the tower 44 except that in some cases it may be unnecessary, particularly where the neutral sulfates are used, to neutralize the extracted oil discharged through the line 66. In any case, however, any occluded sulfate should be removed from the oil by fuller's earth, by hydrolysis and neutralization or by use of other solvents.

In order to thoroughly agitate the oil and extracting agent in the tower 44, any suitable gas may be introduced through line 78 and passed upwardly through the tower. This gas may be some inert gas which does not enter into reaction with any of the constituents in the tower. If any reaction is involved, such as in the use of olefin gases and sulfuric acid, the temperatures must be controlled. The line 78 may also be

used for introducing additional diluent in any of the different modes of operation described above.

The pressure maintained in the tower 4 may vary from 75 to 250 lbs. per square inch in making the alkyl sulfates from olefins, but when the diluted lubricating oil stock is introduced through the line 74 the pressure may be maintained only sufficiently high to keep the diluent in the liquid phase at the temperatures employed. A pressure of at least about 100 lbs. per square inch is preferably used if alkyl sulfates are being made in the operation. The presence of the diluted lubricating oil stock in the tower 4 has a tendency to absorb the olefins and hold them in a position suitable for a controlled reaction with the sulfuric acid.

An extracting medium for use in the process, and comprising normal and acid sulfates and free sulfuric acid, may have a specific gravity of approximately 1.318. This extracting medium made from olefin gases for example, may be capable of producing approximately the following proportions of dry alcohols on hydrolysis: isopropyl 50%; butyl 30%; amyl 12%; hexyl 6%; higher alcohols 2%. The dialkyl sulfates used as extracting media almost without exception have a specific gravity greater than 1. The extracting agents used in accordance with the present invention, serve not only to remove undesirable constituents from the paraffinic type hydrocarbons, but in many cases actually alkylate some of the unsaturated constituents contained in the oil being extracted. Alkylation may also occur where olefins are introduced into contact with the oil in the presence of sulfuric acid. This results in the formation of a more paraffinic molecule from the unsaturated molecules and increases the yield of the raffinate over that which would actually be obtained by the use of other extracting agents. The extracting agents of the present invention furthermore appear to make the resulting oil more readily dewaxed; possibly by the removal of resinous types of compounds which appear to prevent crystallization of paraffin wax. The process is therefore particularly adapted in the treatment of long residuum or cylinder stock and can also be applied to the treatment of slop wax distillates.

As an example of the use of the process and the properties of the treated oils, an original oil having a specific gravity of 0.988; a bromine number of 6.65; and a refractive index of 1.5505, gave a 40% yield of raffinate having a specific gravity of 0.940; a bromine number of 2.56; and a refractive index of 1.5285. The extracted oil in this example had a specific gravity of 1.045; a bromine number of 8.55; and a refractive index of 1.577. These results show a concentration of olefins and aromatics in the extracted oil and a decrease in the specific gravity and refractive index for the raffinate.

A further example of the operation of the process relates to the treatment of a dark green cylinder stock having a viscosity gravity constant (V. G. C.) of 0.87. The resulting product had a V. G. C. of 0.83; a color of 2½ N. P. A., and a carbon residue of 0.38%. Oils of this viscosity (121 sec. Saybolt at 210° F.), when refined by conventional methods, have a carbon residue of about 1½ to 1¾%, and a N. P. A. color of 8. The V. G. C. of 0.83 clearly marks the resulting product as primarily paraffinic in character. In another case, a neutral oil of 200 viscosity at 100° F. and having a V. G. C. of 0.856 when treated

by the process of the present invention, gave a raffinate having a V. G. C. of 0.832. The specific gravity of this oil was decreased from 0.9059 to 0.8927, and the refractive index from 1.5004 to 1.4872. The type of extracting media of the present invention appears to have exceptionally good selectivity for aromatic and unsaturated compounds.

From the foregoing description, it is apparent that various modifications may be made in the operation, and such is contemplated within the meaning of the appended claims.

Having thus described the invention what is claimed as new is:

- 15 1. In the art of refining petroleum lubricating oil stocks, the process which comprises passing the oil stock to be refined through a series of contacting zones in one direction, introducing concentrated sulfuric acid into the last zone of the series, introducing a gas containing olefin into the first zone of the series, reacting the gas with the sulfuric acid to produce a mixture of alkyl sulfates and sulfuric acid, and passing the mixture counter-current to the oil through said series of zones to extract from the oil the non-paraffinic constituents, discharging the extracted oil from the last zone of the series and discharging the alkyl sulfate extract from the first zone of the series.
- 20 2. In the art of refining mineral oils, in which the mineral oil is extracted with a selective solvent for certain constituents of the oil, the improvement which comprises subjecting a mineral oil containing paraffinic, naphthenic and aromatic hydrocarbons to the action of a selective solvent for the naphthenic and aromatic hydrocarbons of relatively high carbon-hydrogen ratio, said solvent comprising a mixture of alkyl sulfate, acid alkyl sulfate, and sulfuric acid in which the alkyl groups of the alkyl sulfates contain not more than six carbon atoms, and separating the extract containing the naphthenic and aromatic hydrocarbons from the remainder of the oil.
- 25 3. In the art of refining mineral oils, the process which comprises separating an oil containing paraffinic compounds and nonparaffinic compounds of the type of naphthenes and aromatics into fractions respectively richer in paraffin and non-paraffinic compounds by extracting said oil with a selective solvent for the naphthenic and aromatic hydrocarbons comprising an acid alkyl sulfate in which the alkyl group contains not more than six carbon atoms.
- 30 4. In the art of refining lubricating oil stocks containing paraffinic, naphthenic and aromatic hydrocarbons, the process which comprises diluting the oil stock with a liquefied normally gaseous hydrocarbon, passing the resulting mixture through a series of zones in which the temperature is controlled, passing an extracting agent comprising an acid alkyl sulfate having a selective solvent action for naphthenic and aromatic hydrocarbons counter-current through said zones to extract from the oil mixture the non-paraffinic hydrocarbons of the type of naphthenes and aromatics, and maintaining a superatmospheric pressure on said zones sufficient to retain said liquefied normally gaseous hydrocarbon in the liquid phase.
- 35 5. In the art of refining mineral oil lubricating stocks, the process which comprises diluting the lubricating oil stock with a substantial proportion of liquefied normally gaseous hydrocarbons, separating such oil containing paraffinic,
- 40 6. In the art of refining mineral oil lubricating stocks, the process which comprises diluting the lubricating oil stock with a substantial proportion of liquefied normally gaseous hydrocarbons, separating such oil containing paraffinic,
- 45 7. In the art of refining mineral oil lubricating stocks, the process which comprises diluting the lubricating oil stock with a substantial proportion of liquefied normally gaseous hydrocarbons, separating such oil containing paraffinic,
- 50 8. In the art of refining mineral oil lubricating stocks, the process which comprises diluting the lubricating oil stock with a substantial proportion of liquefied normally gaseous hydrocarbons, separating such oil containing paraffinic,
- 55 9. In the art of refining mineral oil lubricating stocks, the process which comprises diluting the lubricating oil stock with a substantial proportion of liquefied normally gaseous hydrocarbons, separating such oil containing paraffinic,
- 60 10. In the art of refining mineral oil lubricating stocks, the process which comprises diluting the lubricating oil stock with a substantial proportion of liquefied normally gaseous hydrocarbons, separating such oil containing paraffinic,
- 65 11. In the art of refining mineral oil lubricating stocks, the process which comprises diluting the lubricating oil stock with a substantial proportion of liquefied normally gaseous hydrocarbons, separating such oil containing paraffinic,
- 70 12. In the art of refining mineral oil lubricating stocks, the process which comprises diluting the lubricating oil stock with a substantial proportion of liquefied normally gaseous hydrocarbons, separating such oil containing paraffinic,
- 75 13. In the art of refining mineral oil lubricating stocks, the process which comprises diluting the lubricating oil stock with a substantial proportion of liquefied normally gaseous hydrocarbons, separating such oil containing paraffinic,

naphthenic and aromatic hydrocarbons into fractions respectively richer in paraffinic and non-paraffinic compounds by extracting the oil with a selective solvent for naphthenic and aromatic hydrocarbons comprising an alkyl sulfate mixture produced by reacting a mixture of gaseous olefins with sulfuric acid.

6. The process of refining petroleum oil as defined by claim 1 in which the gas containing olefin is intimately contacted with the sulfuric acid mixture in each zone to produce agitation of the sulfuric acid mixture and the oil being extracted.

7. In the art of refining petroleum lubricating oil stocks containing paraffinic and naphthenic hydrocarbons in which the naphthenic hydrocarbons are extracted from the lubricating oil stock in an extraction operation, the improvement which comprises dissolving the lubricating oil stock to be extracted and refined in a liquefied normally gaseous hydrocarbon diluent and passing the resulting diluted mixture through a series of contacting zones in one direction, in-

5 troducing concentrated sulfuric acid into the last zone of the series and passing it through the series of zones countercurrent to the oil stock, introducing a mixture of gases containing olefins into the first zone of the series and passing them through the series of zones in intimate contact with the oil and the sulfuric acid under conditions adapted to react the olefins with the acid to form alkyl sulfates which are passed through the zones with any unreacted sulfuric acid to comprise an extracting medium for removing said naphthenic hydrocarbons from the oil, discharging the dilute extracted oil substantially free of naphthenic hydrocarbons from the last zone of the series and discharging the acid extract mixture containing the naphthenic hydrocarbons from the first zone of the series.

8. The process as defined by claim 7 in which the dilute extracted oil discharged from the last zone of the series is contacted with a clay refining agent to neutralize the oil.

WILLIAM E. FORNEY.
